UNITED STATES PATENT OFFICE

RAYMOND J. JENKINS, OF BALTIMORE, MARYLAND

SMOKE PIPE AIR CHECK

Application filed March 19, 1931. Serial No. 523,847.

This invention relates to certain new and useful improvements in smoke pipe air checks especially adapted to be used in connection with domestic heating plants, the object being to provide an air check which will operate efficiently on either a horizontal or vertical type of heating plant.

Another object of my invention is to provide a smoke pipe air check which is exceedingly simple and cheap in construction, the same being formed of a sheet of metal rolled into its proper form so as to provide a pipe section with a plurality of substantially semi-circular shaped pockets for feeding air into the interior of the pipe section to regulate the combustion so that a considerable economy in the consumption of fuel will be obtained.

Another object of my invention is to provide novel means for holding the damper sleeve for regulating the admission of air in position on the casing so that it can be readily turned and held in its adjusted position.

A still further object of the invention is to provide a smoke pipe air check with a damper by means of which the draft can be regulated to a nicety.

Other and further objects and advantages of the invention will be hereinafter set forth and the novel features thereof defined by the appended claims.

In the drawing,

Figure 1 is a vertical section through my improved construction of smoke pipe air check;

Figure 2 is a horizontal section taken on line 2-2 of Figure 1;

Figure 3 is a detail perspective view of a portion of a check showing the substantially semi-circular shaped pocket; and

Figure 4 is a detail enlarged elevation showing the manner of holding the damper sleeve in an adjusted position.

In the preferred embodiment of my inven-

tion, I take a sheet of metal 1 and roll the same so as to form a plurality of pockets 2 which are substantially semi-circular in cross section and are provided with closed ends 3, these pockets being provided with air openings 4 for the purpose hereinafter fully described.

The sheet of metal thus formed with the pockets is preferably rolled into cylindrical form to form a pipe section, the meeting edges being preferably welded together. When the sheet of metal is rolled to produce the pockets, lateral beads 5 and 6 are formed which provide a guideway for a collar 7 which is revolvably mounted within the guideway and is provided with openings 8 adapted to register with the pockets so as to allow air to be fed into the interior of the pipe section to mingle with the products of combustion in order to produce the desired result which is well known in the art.

The ends of the collar 7 are provided with lateral flanges 9 and 10 which are apertured and the flange 10 is provided with extensions 11 between which is mounted a cam 12 carried by a shaft 13 having a handle 14 for turning the same. This cam is adapted to engage the heads 15 of bolts 16 which passes through the apertures of the flanges 9 and 10 and have nuts 17 threaded thereon at one end.

Disposed between the head 15 and the bolt 16 and the flange 10 is a coil spring 18 which normally has the tendency to draw the two flanges together in order to hold the collar or band tightly within the guideway formed by the beads 5 and 6 so as to form a substantially air tight joint between the collar and the outer circumference of the cylindrical stove pipe section.

By this construction, when the shaft 13 is turned through the medium of the handle 14, the head of the bolt will be forced towards the flange 10 so as to compress the spring 18 which allows the flanges 9 and 10 to separate to facilitate the revolving or turning of the

collar in the guideway. After the collar has been moved into its adjusted position by turning the handle 14, the high portion of the cam will be turned out of engagement with the head 15 of the bolt so as to release the tension of the spring which has been energized by the operation of the cam so as to allow said spring to deenergize and force the two flanges 9 and 10 together in order to hold the collar in its adjusted position.

This provides a construction by means of which an automatic damper control can be attached to the smoke pipe air check when desired and also provides means for insuring the collar being held in its adjusted position and facilitates the revolving of the collar in its guideway by reducing the friction between the inner faces of the collar and the outer face of the stove pipe section.

20 When the sheet is rolled to form the pockets an interior bead 19 is formed adjacent one end which forms a stop adapted to be engaged by the outlet flue of the boiler or heating plant and the opposite end is slightly reduced so that it can extend into a stove pipe section or into a flue.

While I have shown a smoke pipe air check constructed of a sheet of metal rolled in this particular manner, I am aware that a cylindrical stove pipe section could be utilized with openings punched therein and a series of separate substantially semi-circular pockets could be attached to the inner wall so as to form air feeding means.

35 It will be noted that these pockets are arranged on the interior of the pipe section in such a manner that a space is left between the same which allows the air entering the 40 products of combustion passing through the pipe section.

In order to be able to control the draft through the smoke pipe air check to a nicety, I dispose therein a butterfly damper 20 45 which is carried by a shaft 21 provided with a handle 22 for operating the same, said damper having a diameter slightly less than the diameter of a radius drawn to meet the inner walls of the substantially semi-circular pockets by means of which the draft through the pipe section can be regulated and it will be noted that this damper will not completely cut off the draft through the 50 pipe section as there will always be an open space between the pockets through which the products of combustion can pass to the flue.

55 From the foregoing description it will be seen that I have provided a smoke pipe air check which can be manufactured very 60 cheaply and which is provided with a plurality of pockets disposed circumferentially around the interior of a cylindrical pipe section having means at the lower ends for delivering air into the volume of smoke products of combustion passing therethrough,

said pockets having air admitting openings at their upper ends which are controlled by a revoluble sleeve held in its adjusted position in such a manner that it can be readily revolved and be retained in its adjusted position.

70 While I have shown and described a particular manner of making my improved construction of smoke pipe air check, I wish it to be understood that I do not wish to confine myself to any particular manner of forming the pipe section as I am aware that this pipe section can be formed in various ways and that the pockets can be formed either integral or separate as my invention 75 consists broadly in disposing within a pipe section a plurality of pockets which are provided with air admitting openings at their upper end from the atmosphere and air delivering openings at their lower end adapted 80 to deliver streams of air into the volume of products of combustion passing through the pipe section.

85 Disposed between the flanges 9 and 10 of the collar is a spacer block 23 which is provided with apertures to receive the bolts 16 and is provided with a curved inner face corresponding to the curvature of the casing so that the space between the flanges will be 90 filled in order to form a tight joint when the 95 collar is in adjusted position.

95 In the operation of my improved construction of smoke pipe air check when placed in a smoke pipe between the heating plant and the chimney, it will be noted that the annularly disposed pockets receive air from the atmosphere at one end and deliver this air into the volume of products of combustion passing through the device at the other end, said air being first heated and as 100 these air streams are arranged entirely around the interior of the pipe, a plurality of air streams enter the flue so as to commingle with the products of combustion and to regulate the draft and by having the collar 105 mounted on the periphery of the pipe section with a plurality of openings, this collar can be adjusted so as to regulate the area of the openings and as these pockets are placed entirely around the pipe, these openings 110 can be adjusted so as to register with the space between the pockets to completely 115 cut off the entering of air.

120 It will also be seen that by having the collar mounted in a guideway, it is held in its proper position so as to prevent any danger of the same moving longitudinally and by having the means for holding the collar under tension in position, I provide a tight joint between the collar and the circumference of the pipe so that when desired the air 125 can be completely cut off as leakage is prevented by this construction.

130 This construction also provides means for loosening the collar in order to allow it to

be manually operated and when the collar has been set in position so as to admit air through the openings formed therein into the pockets, these streams of air are delivered into the volume passing through the pipe in all directions and it will be noted that these pockets are spaced so that the volume of products of combustion pass entirely around the outlet openings of the pockets.

10 By having the pockets spaced when the butterfly damper is in closed position, a plurality of separate flues are formed between the pockets so that the check valve can never be completely closed.

15 Devices of this kind have been used and found entirely satisfactory in use and it has been found by experimenting that the stack will be maintained cooler with such a device and that there will be a great saving of fuel.

20 What I claim is:

1. A smoke pipe air check of the kind described formed of a sheet of metal rolled into cylindrical form and having pockets expanded inwardly therefrom provided with lateral outlet openings at one end, said pockets being closed by a band, said band being provided with air inlet openings for feeding air into said pockets.

25 2. A smoke pipe air check of the kind described comprising a cylindrical casing having on its interior a plurality of spaced inwardly extending pockets provided with lateral outlet openings at one end, said pockets forming a plurality of annularly arranged unobstructed flues between the respective pockets, means for admitting air at the other end of said pockets and a butterfly damper arranged within said casing and adapted to close the central area of said pipe section between said pockets.

30 3. A smoke pipe air check of the kind described comprising a cylindrical apertured casing having a collar revolubly mounted on the circumference thereof provided with air inlet openings, said collar being provided with lateral flanges at its ends, a bolt extending through said flanges having a coil spring surrounding a portion thereof and a cam carried by said collar adapted to engage said bolt for compressing said spring.

35 4. An air check of the kind described comprising a cylindrical casing having openings, a collar surrounding said casing having air inlet openings for admitting air through the openings of said casing, said collar being provided with lateral apertured flanges, a bolt extending through the apertures of said flanges, a spring surrounding said bolt for drawing said flanges towards each other, a cam carried by one of said flanges adapted to engage said bolt for compressing said spring to allow said flanges to move away from one another.

40 5. As a new article of manufacture, a

smoke pipe air check comprising a casing formed from a single sheet of metal having a plurality of internal air chambers provided with outlet openings, a collar revolubly mounted on said casing provided with openings for admitting air to said chambers, means for holding the ends of said collar together under tension and means creating and for releasing said tension.

In testimony whereof I hereunto affix my signature.

RAYMOND J. JENKINS.
